DESIGN FOR A DOOR KNOCKER

James I. Hoag, Ottumwa, Iowa

Application February 17, 1941, Serial No. 99,035

Term of patent 7 years

To all whom it may concern:

Be it known that I, James I. Hoag, a citizen of the United States and a resident of Ottumwa, in the county of Wapello and State of Iowa, have invented a new, original, and ornamental Design for a Door Knocker, of which the following is a specification, reference being had to the accompanying drawing, forming part thereof, in which:

I claim:

The ornamental design for a door knocker, as shown.

JAMES I. HOAG.
